Primary Examiner — Kevin Rudzinski*Assistant Examiner* — Sean D Lough(74) *Attorney, Agent, or Firm* — Daniel N. Smith(57) **CLAIM**

The ornamental design for a violin cushioning device, as shown and described.

DESCRIPTION

FIG. 1 is a top perspective view of the violin cushioning device showing my new design;

FIG. 2 is a top view of the violin cushioning device showing my new design;

FIG. 3 is a side view of the violin cushioning device showing my new design;

FIG. 4 is another side view of the violin cushioning device showing my new design; and,

FIG. 5 is a top perspective view of the violin cushioning device attached to the lower bout ribs, lower bout purfling edges, end pin, saddle, and tail gut of a violin showing my new design in a position of use attached to the above described environment at the base of a violin.

The broken lines depicted in FIG. 5 illustrate environment of the violin cushioning device that forms no part of the claimed design.
